UNITED STATES PATENT OFFICE.

HERBERT S. JANDUS AND WILLIAM MEYERHUBER, OF DETROIT, MICHIGAN, ASSIGNORS TO THE C. G. SPRING & BUMPER COMPANY, OF DETROIT, MICHIGAN, A CORPORATION OF DELAWARE.

DESIGN FOR A CLAMP PLATE.

Application filed March 7, 1928. Serial No. 25,744. Term of patent 14 years.

To all whom it may concern:

Be it known that we, HERBERT S. JANDUS and WILLIAM MEYERHUBER, citizens of the United States and Germany, respectively, residing at Detroit, in the county of Wayne and State of Michigan, have invented a new, original, and ornamental Design for Clamp Plate, of which the following is a specification, reference being had to the accompanying drawing, forming part hereof, wherein—

Fig. 1 represents a front elevation and Fig.

2 represents a side elevation of a clamp plate exhibiting our new design. The head of a bolt for clamping the plate is shown in dotted lines.

We claim:

The ornamental design for a clamp plate, substantially as shown and described.

HERBERT S. JANDUS.
WILLIAM MEYERHUBER.
